PUMP, SYRINGE, AND LIKE APPLIANCE FOR
SURGICAL AND MEDICAL AND OTHER
PURPOSES

Hans Herbert Schulz, London, England

Application December 17, 1935, Serial No. 54,811
In Great Britain December 19, 1934

17 Claims. (Cl. 128—237)

This invention relates to syringes and like hand appliances, especially suitable for use for surgical or medical purposes.

It is most desirable in syringes particularly for those intended for medical or surgical use, such as vaginal syringes, that the nozzle end should be of as simple a shape as possible and without taps or external valves, that any controls should be remote of away from such end, that the instrument should be operable with one hand, and that the rate of discharge should be regulatable by a valve or the like and not be dependent on hand pressure. Further desiderata are that the instrument should be compact and portable and that in use it should not require any attachments to other parts, e. g. pumps.

The main object of the present invention is to provide a syringe fulfilling all these desiderata, and which further is of such construction that it can be manufactured of substances which permit of the exterior being easily cleaned and sterilized.

According to the present invention a syringe or the like appliance is provided with an inner cylinder, surrounded by an outer rubber sleeve, normally in close proximity therewith, and attached to the cylinder in a fluid tight manner, so that when fluid is forced through a non-return valve in the cylinder a storage space, formed by the circumferential extension of the rubber sleeve, is filled by liquid. Upon the actuation of a valve providing a variable and controllable aperture the liquid so stored is discharged under the pressure exerted by the rubber sleeve through a discharge tube and nozzle, but no hand pressure is required on the bulb. The same tube is used for charging the cylinder and for the discharge of the liquid.

The valve controlling the outflow is preferably at or near the end of the cylinder opposite to the nozzle end and is preferably of the cone type, and the non-return valve into the contractible storage space is preferably formed by a rubber band.

The syringe is preferably filled by the pumping action of a piston integral with or attached to the nozzle.

A case can be conveniently constructed for use with the syringe as is hereinafter illustrated, the cap being internally screwed, such screw co-operating firstly with screw threads on the body of the syringe and subsequently with like threads on the body of the casing. By this method the screwing on of the cap first presses the nozzle into the syringe, and then fixes the cap on the body of the case.

In a modification the syringe may be adapted to be filled from a tap by fitting a member either in substitution for, or in addition to, the nozzle or by the removal of the nozzle. The pump fitting means may be omitted where it is desired to rely only upon tap filling.

The syringe and its container can be constructed almost entirely of a phenolic condensation product, or like substance, and rubber, so as to be of very light weight and readily cleaned disinfected and dried.

Examples of apparatus made according to the invention will now be more particularly described by reference to the accompanying drawings.

Figure 1 is a longitudinal section of a syringe made according to this invention, the case being shown in dotted lines. Figure 2 is a longitudinal section of the case. Figure 3 is a detail sectional view of a variant form of pump cylinder. Figure 4 is a sectional view showing a nozzle and removable catheter, and in dotted outline a water tap faucet for filling after the catheter has been removed. Figure 5 is a sectional view showing a nozzle and removable catheter also adapted for filling by a water tap. Figure 6 is a sectional view showing an attachment for filling from a tap. Figure 7 is a sectional view showing an adjustable fitting on a nozzle, more particularly for use as a spray. Figure 8 is a view of a detachable nozzle and Fig. 9, a modified form of discharge valve.

In the vaginal syringe illustrated in Figure 1 a piston 1 with a suction flap valve 2 moves in a cylinder 3 by which movement fluid can be pumped into the cylinder, through the tubular extension 4 of the piston. This extension may form the socket part to which a spigot part 5 is detachably secured, the part 5 terminating in a nozzle 6, which may be constructed so as to be interchangeable. The spigot part 5 when detached from the part 4 may be housed in the latter. Charging of the cylinder 3 is from the nozzle end and pumping may take place while the two-part arrangement is in its extended position.

The two-part arrangement may be dispensed with and the nozzle placed on the end of the tubular extension as shown in Fig. 8. The parts 4 and 5 form the catheter component of a vaginal syringe.

The spigot tube 5 in its extended position may have an oblique or angular setting with respect to the socket tube 4. One way of setting is by a screw union 6a inclined at an angle to the longitudinal axis of the socket tube 4. An overlap connection as shown in Fig. 1 is provided be-

tween the two tubes to prevent disconnection.

The pump may have an automatically actuated return stroke effected by, for example, a sleeve 7 of rubber anchored to the piston at one end, and to the end wall of the cylinder at its other end.

The barrel or cylinder 3 is surrounded by an elastic wall 8 which by circumferential expansion forms a contractile storage chamber 9 between the elastic wall and the cylinder wall. The wall 8 is secured in a fluid tight manner at its ends between flanges 11 on the cylinder wall, and flanges 12a on the end covers 12 of the cylinder.

15 The piston on its discharge stroke forces the fluid from the cylinder through a non-return valve controlled inlet 10 into the storage chamber. The non-return valve is shown as a rubber band 10a.

20 In the cylinder end wall 13 there is a valve seat against which a rotary valve 14 fits. 14a is the valve port and 15 the storage chamber discharge port.

The stem 16 of the valve 14 projects through 25 the end cap 12 of the cylinder and has an index disc 17 and a pin 18 working in a groove 19 for setting the valve 14. For discharge the valve may be positioned so that its port 14a wholly or partly registers with the storage chamber port 15 whereby the rate of discharge may be regulated.

30 Instead of a rotary valve a slide or push valve may be used. As shown in Fig. 9, 110 is a slide or push valve which for discharge is positioned by a sliding movement against a spring 111 so that the valve port 112 wholly or partly registers with the storage chamber port 15.

The valve 14 has a tubular extension 14b through which the fluid on discharge passes to the spigot and socket tubes 4 and 5 and out 40 through the nozzle 6. This tubular extension 14b also serves as a centre guide for the piston 1.

The appliance is adapted to fit into a small cylindrical container illustrated in Fig. 2 which may be made of a phenolic condensation product or like substance, so that it is protected from bacterial contamination, and the container conceals the nature of the contents. That shown is a two-part container 20, 21, the part 21 having a chamber 22 serving as a holder for a supply of packets or capsules of any desired substance e. g., an antiseptic. The other part 20 has one component 23 of a screw union, the other component 24 of which is on one end-cap of the cylinder so that the appliance is held 55 from movement within the container. The component 23 may be common to both the component 24 and a component 25 on the part 21 of the container.

In the modification shown by Fig. 3 the piston 60 is solid and the tubular extension 14b serves as a suction tube, the fluid passing into the cylinder through a suction valve 14c consisting of a rubber band.

The cylinder or the piston and telescopic arrangement may be reciprocated or pulsated for pumping the fluid. When the cylinder is pulsated or reciprocated the nozzle end of the telescopic construction may be held against the bottom of a bowl of liquid.

70 An intermediate chamber similar to that shown by 104 in Fig. 6 may be provided in the discharge passage in which disinfectant tablets may be inserted.

Fig. 4 shows a detachable nozzle component 75 100, so that after the removal thereof the fill-

ing is effected by a water-tap 101. Fig. 5 also shows a detachable nozzle component 102, the apparatus being filled by a water-tap after the removal of the nozzle component. Fig. 6 is a further example of an apparatus adapted to be 5 filled from a water-tap by removal of the discharge nozzle and fitting a connector 103. This connector 103 may have means 104 for holding disinfectant tablets. In all these constructions the pump fitting means may be omitted. 10

Fig. 7 shows an adjustable fitting 104a whereby the nozzle openings 105 may be regulated so as to provide a regulatable discharge.

Apparatus according to the present invention is well suited for manufacturing by moulding 15 processes.

What I claim is:—

1. A syringe of the kind referred to comprising a filling tube which acts also as a discharge tube, an inner rigid cylinder or barrel, an outer elastic sleeve normally in close proximity therewith and attached thereto in a fluid tight manner so as to form a contractile storage space, a one-way valve controlled inlet to said storage space through which said storage space 20 is filled, a discharge outlet from said storage space through which the fluid so stored is discharged under pressure exerted by the elastic sleeve, and a manually operated regulatable valve for said discharge outlet, the valve being 25 operated from a point at or near to the end farthest from the nozzle and discharge tube.

2. A syringe of the kind referred to comprising a filling and discharge tube, an inner rigid cylinder or barrel, a piston fitted therein, a pump section valve for passing the fluid to the cylinder, an outer elastic sleeve normally in close proximity with said cylinder or barrel and attached thereto in a fluid tight manner so as to form a contractile storage space, a one-way 35 valve controlled inlet from said cylinder to said storage space through which said storage space is filled, said piston and said cylinder being relatively displaceable so as to cause fluid to pass by the suction valve into the cylinder during one 40 stroke and to be forced through the inlet to the storage space on the return stroke and a valve controlled discharge outlet from said storage space through which the fluid so stored is discharged under the pressure exerted by the elastic sleeve. 50

3. A syringe of the kind referred to comprising an inner rigid cylinder or barrel, a piston fitted therein, a pump suction valve for passing the fluid to the cylinder, a filling and discharge tube attached to said piston, an outer elastic sleeve normally in close proximity with said cylinder or barrel and attached thereto in a fluid tight manner so as to form a contractile storage space, a one-way valve controlled inlet from said cylinder to said storage space through which said storage space is filled, and a valve controlled discharge outlet from said storage space through which the fluid so stored is discharged under the pressure exerted by the elastic sleeve. 60

4. A syringe of the kind referred to comprising an inner rigid cylinder or barrel, a piston fitted therein, said piston and cylinder being relatively displaceable for pumping fluid, a resilient member for causing movement in one direction, a 70 valve through which the fluid is pumped into the cylinder, an outer elastic sleeve normally in close proximity with said cylinder or barrel and attached thereto in a fluid tight manner so as to form a contractile storage space, a one-way 75

valve controlled inlet from said cylinder to said storage space through which said storage space is filled, and a valve controlled discharge outlet from said storage space through which the fluid so stored is discharged under the pressure exerted by the elastic sleeve.

5. A syringe of the kind referred to comprising an inner rigid cylinder or barrel, a piston fitted therein, a valve through which the fluid is forced into the cylinder, said piston being prolonged in the form of a tube comprising socket and spigot parts passing through and projecting beyond an end wall of the cylinder, an outer elastic sleeve normally in close proximity with said cylinder or barrel and attached thereto in a fluid tight manner so as to form a contractible storage space, a one-way valve controlled inlet from said cylinder to said storage space through which said storage space is filled, and a valve controlled discharge outlet from said storage space through which the fluid so stored is discharged under the pressure exerted by the elastic sleeve.

6. A syringe of the kind referred to comprising a filling and discharge tube consisting of socket and spigot parts, an inner rigid cylinder or barrel, an outer elastic sleeve normally in close proximity therewith and attached thereto in a fluid tight manner so as to form a contractible storage space, a one-way valve controlled inlet to said storage space through which said storage space is filled, a valve controlled discharge outlet from said storage space through which the fluid so stored is discharged under the pressure exerted by the elastic sleeve, and means for detachably securing said socket and spigot parts together to provide an elongated filling and discharging tube, said parts being constructed so that when detached they can be located one within the other and the two parts at least in part housed in said cylinder.

7. A syringe of the kind referred to comprising an inner rigid cylinder or barrel, a piston fitted therein, a valve for forcing the fluid into the cylinder, an outer elastic sleeve normally in close proximity with said cylinder or barrel and attached thereto in a fluid tight manner so as to form a contractible storage space, a one-way valve controlled inlet from said cylinder to said storage space through which said storage space is filled, a discharge outlet from said storage space through which the fluid so stored is discharged under the pressure exerted by the elastic sleeve, and a valve for said discharge outlet, said valve having a tubular extension through which the fluid is discharged and serving as a centre guide for the piston.

8. A syringe of the kind referred to comprising an inner rigid cylinder or barrel, a piston fitted therein, said piston and said cylinder being relatively displaceable so as to form a pump, an outer elastic sleeve normally in close proximity with said cylinder or barrel and attached thereto in a fluid tight manner so as to form a contractible storage space, a one-way valve controlled inlet from said cylinder to said storage space through which said storage space is filled, a discharge outlet from said storage space through which the fluid so stored is discharged under the pressure exerted by the elastic sleeve, a valve for said discharge outlet, said valve having a tubular extension through which the fluid is discharged, an aperture in the wall of said tubular extension, and a pump suction valve controlling said aperture and opening on the suction stroke of the

pump to allow for the passage of fluid through said extension into the cylinder.

9. A syringe of the kind referred to comprising a filling and discharge tube, an inner rigid cylinder or barrel, a piston fitted therein, a suction valve in said piston through which the fluid is forced into the cylinder, an outer elastic sleeve normally in close proximity with said cylinder or barrel and attached thereto in a fluid tight manner so as to form a contractible storage space, a one-way valve controlled inlet to said storage space through which said storage space is filled from said cylinder, a discharge outlet from said storage space through which the fluid so stored is discharged under the pressure exerted by the elastic sleeve, and a manually operated regulatable valve for said discharge outlet.

10. A syringe of the kind referred to comprising a filling and discharge tube, an inner rigid cylinder or barrel, a piston fitted therein, a suction valve in said piston through which the fluid is forced into the cylinder, an outer elastic sleeve normally in close proximity with said cylinder or barrel and attached thereto in a fluid tight manner so as to form a contractible storage space, a one-way valve controlled inlet to said storage space through which said storage space is filled from said cylinder, a discharge outlet from said storage space through which the fluid so stored is discharged under the pressure exerted by the elastic sleeve, a manually operated regulatable valve for said outlet, a tubular extension of said valve through which the fluid is discharged said extension also serving as a centre guide for the piston.

11. A syringe of the kind referred to comprising a filling and discharge tube, an inner rigid cylinder or barrel, a piston therein, said piston and cylinder being relatively displaceable, a pump suction valve, a resilient member anchored to the piston at one end, and to the end wall of the cylinder at the other end, said member serving to return the cylinder and piston into their normal position after relative displacement, an outer elastic sleeve normally in close proximity with said cylinder or barrel and attached thereto in a fluid tight manner so as to form a contractible storage space, a one-way valve controlled inlet to said storage space through which said storage space is filled from said cylinder, and a valve controlled discharge outlet from said storage space through which the fluid so stored is discharged under the pressure exerted by the elastic sleeve.

12. A syringe of the kind referred to comprising an inner rigid cylinder or barrel, an outer elastic sleeve normally in close proximity therewith and attached thereto in a fluid tight manner so as to form a contractible storage space, a one-way valve controlled inlet to said storage space through which said storage space is filled, a discharge outlet from said storage space through which the fluid so stored is discharged under the pressure exerted by the elastic sleeve, a manually operated regulatable valve for said discharge outlet, and means for setting said regulatable valve.

13. A syringe or the like of the kind referred to comprising an inner rigid hollow cylinder or barrel, an outer elastic sleeve normally surrounding said cylinder and lying in close proximity therewith, a filling tube connected to said cylinder, said tube also acting as a discharge tube, said sleeve being attached to the cylinder in a fluid-tight manner and being adapted to be ex-

- 5 panded and elastically energized by fluid pressure so as to form a variable storage space between the sleeve and the outer wall of the cylinder, a fluid inlet from the interior of said cylinder
5 to said storage space and a one-way valve for controlling the admission through such inlet of fluid by which said sleeve is elastically expanded and the storage space filled, a discharge outlet from said storage space through which the fluid
10 so stored can be discharged under the pressure exerted by the elastically energized sleeve, and a manually operable valve for controlling the discharge through said outlet, said one-way valve being arranged to trap a quantity of fluid in
15 said storage space when said discharge valve is closed.

14. A syringe according to claim 13, having external screw threads on the body, at or near the nozzle end, and provided with a case the body
20 of which has at its upper end screw threads forming a continuation of those above mentioned, and a cap having internal screw threads of similar pitch adapted to co-operate firstly with the screw threads on the syringe and then with the screw
25 threads on the case body to secure the cap to the case.

15. A syringe or the like of the kind referred to comprising an inner rigid cylinder or barrel, an outer elastic sleeve normally surrounding said
30 cylinder and lying in close proximity therewith, said sleeve being attached to the cylinder in a fluid-tight manner and being adapted to be expanded and elastically energized by fluid pressure so as to form a variable storage space between the sleeve and the outer wall of the cylinder, a filling tube which also acts as a discharge tube leading to said cylinder, a fluid inlet to said storage space from said cylinder and a one-way valve at such inlet for controlling the admission through such inlet of fluid by which said
35 sleeve is elastically expanded and the storage space filled, a discharge outlet from said storage space through which the fluid so stored can be discharged under the pressure exerted by the
40 elastically energized sleeve from the same end of the said tube as that used for filling, and a valve arranged to be hand-operated by the user for controlling the discharge through said outlet, said one-way valve being arranged to permit a
45 quantity of fluid to be trapped in said storage space when said discharge valve is closed.

16. A syringe or the like of the kind referred

to comprising an inner rigid hollow cylinder or barrel, an outer elastic sleeve normally surrounding said cylinder and lying in close proximity therewith, said sleeve being attached to the cylinder in a fluid-tight manner and being adapted 5 to be expanded and elastically energized by fluid pressure so as to form a variable storage space between the sleeve and the outer wall of the cylinder, a fluid inlet from the interior of said cylinder to said storage space and a one-way valve at such inlet for controlling the admission through such inlet of fluid by which said sleeve is elastically expanded and the storage space filled, a discharge outlet from said storage space through which the fluid so stored can be discharged 10 under the pressure exerted by the elastically energized sleeve, and a valve for controlling the discharge through said outlet, and an adjustable discharge nozzle at the discharge end of the syringe which is capable of being set in 15 any one of several positions for regulating the discharge, said discharge end of the syringe having an opening through which the fluid enters the syringe during filling, said adjustable nozzle being situated in said opening.

17. A syringe or the like of the kind referred to comprising an inner rigid hollow cylinder, an outer elastic sleeve normally surrounding said cylinder and lying in close proximity therewith, a filling opening communicating with the interior 30 of said cylinder, said filling opening also serving as a discharge opening, said sleeve being attached to the cylinder in a fluid-tight manner and being adapted to be expanded and elastically energized by fluid pressure so as to form a variable storage 35 space between the sleeve and the outer wall of the cylinder, a fluid inlet from the interior of said cylinder to said storage space and a one-way valve for controlling the admission through such inlet of fluid by which said sleeve is elastically 40 expanded and the storage space filled, a discharge outlet from said storage space through which the fluid so stored can be discharged under the pressure exerted by the elastically energized sleeve, a valve for controlling the discharge 45 through said outlet, said one-way valve being arranged to trap the fluid in the said storage space when said discharge valve is closed, and means for filling said syringe through said common filling and discharge opening direct from 50 a tap.

HANS HERBERT SCHULZ.
